CLAUS NISSEN RIIBER, OF TRONDHJEM, NORWAY, ASSIGNOR TO NORSK ALKALI A/S
OF TRONDHJEM, NORWAY.

ELECTROLYZING APPARATUS.

1,337,724.

Specification of Letters Patent. Patented Apr. 20, 1920.

Application filed March 27, 1919. Serial No. 285,669.

To all whom it may concern:

Be it known that I, CLAUS NISSEN RIIBER, of Hans Hagerups Gate 8, Trondhjem, in the Kingdom of Norway, have invented certain new and useful Improvements in Electrolyzing Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 In electrolyzing apparatus particularly adapted for the electrolysis of alkaline chlorids, in which the anode liquid has to pass through a horizontal or substantially horizontal diaphragm, the latter consists of 20 a porous layer distributed upon a perforated or reticulated support which is generally of metal and thus constituting the cathode of the apparatus. This porous layer may consist, for instance, of asbestos boards or cloth 25 upon which is placed a layer of a pulverulent stable material; or the porous layer may consist only of a pulverulent or fibrous mass.

In this type of apparatus, when it is desired to obtain a strong lye with a good current output, it is important that at every point of the diaphragm surface equal quantities of liquid pass through in each square centimeter. It has been found, however, 35 that it is difficult to obtain this result at the line of contact between the vertical walls of the electrolyzing vessel and the diaphragm. Even, when no crevices are present at this point the liquid will pass more easily along 40 the said surface of contact than through the small particles of the diaphragm mass.

The anode liquid which thus passes through more rapidly will of course become a thinner lye than that which passes through 45 at other points of the diaphragm. This circumstance involves an unnecessary dilution of the liquor of the electrolyzing apparatus and this again involves higher evaporation costs during the further treatment of the 50 lye.

According to the present invention these difficulties are avoided by placing upon the diaphragm or partially embedding in the body of the same and at a short distance 55 from the walls of the anode chamber suit-

able members such as fillets, rods, pipes or other bodies of a suitable shape and made of material with high capacity of resistance, for instance hardburned stoneware, china, glass or concrete, in such manner that the 60 top of said members is situated above the diaphragm surface. Obviously a frame consisting of one single piece may be employed, this being particularly suitable in the case of small apparatus.

65 The trough-shaped space which is thereby formed and which runs along the walls of the anode compartment is supplied, if necessary up to the top edge of said members, with a pasty tightening mass consisting for 70 instance of a fine powder of asbestos, alumina, clay, sulfate of barium or oxid of iron, into which is incorporated a suitable quantity of water or a salt solution. By this arrangement there is provided quite a thick 75 tightening layer along the edges, whereby the velocity of the passage of the liquid is reduced to the desired degree.

An embodiment of the invention is illustrated in the accompanying drawing, where- 80 in:

Figure 1 is a sectional view of an electrolytic cell constructed in accordance with the invention, and

Fig. 2 is a sectional view on an enlarged 85 scale showing a detail of the arrangement.

In the illustrated example, 1 is the wall of the cathode compartment and 6 is the wall of the anode compartment. A grate 2 supports a screen 2^a which is covered by a 90 layer of porous material 3. A frame 4 is embedded in the diaphragm layer near to and along the wall 6 and the space between this frame and the wall 6 is filled with a pasty mass 5 of the character above referred to.

Claims:

1. Electrolytic apparatus comprising a substantially horizontal diaphragm consisting of a layer of loose porous material, an 100 anode-chamber wall about said diaphragm, a member of stable material in said chamber and spaced from said wall to form a trough adjacent the wall, and a layer of pasty, liquid-penetrable material in said trough.

2. In electrolyzing apparatus with a horizontal or substantially horizontal diaphragm comprising a loose layer of porous pulverulent material, members of stable material upon and partly embedded in said dia- 110

phragm, said members being spaced from the lines of contact between the diaphragm and the walls of the anode compartment to form a trough adjacent said walls and a 5 layer of pasty, liquid-penetrable material in said trough.

3. An electrolyzing apparatus as described in claim 2 in which the trough-forming members consist of a single frame wholly 10 immersed in the liquid.
4. An electrolyzing apparatus as described

in claim 2 in which the trough-forming members consist of a number of structural elements as described.

In testimony that I claim the foregoing as 15 my invention I have signed my name in presence of two subscribing witnesses.

CLAUS NISSEN RIIBER.
